LEVERETT W. TIFFANY, OF WINSTED, CONNECTICUT.

LEVEL ATTACHMENT.

Application filed November 8, 1921. Serial No. 513,675.

To all whom it may concern:

Be it known that I, LEVERETT W. TIFFANY, a citizen of the United States, and resident of Winsted, in the county of Litchfield and State of Connecticut, have invented a new and Improved Level Attachment, of which the following is a full, clear, and exact description.

My invention relates to an attachment, 10 and more particularly aims to provide a device of this nature which is intended to be associated with a level.

It is an object of this invention to provide a device of the character stated which 15 may be manufactured at a nominal figure and which may be applied to a standard type of level, and by means of which the distance between two planes extending in a single surface may be measured.

20 Still another object of this invention is the provision of an attachment of the type specified which shall be similar to the attachment described in my co-pending application Serial No. 513,674, filed Nov. 8, 1921, 25 but which is ideally adapted for use in connection with work which requires great exactitude.

Still further objects of this invention will 30 become apparent in the annexed specification taken in connection with the drawings, which latter illustrate one practical embodiment of the same, and in which—

Figure 1 is a side elevation of a level and 35 showing my improved attachment associated with one end thereof.

Figure 2 is a fragmentary partly sectional enlarged view of the end portion of a level showing the attachment in position thereon, and

40 Figure 3 is an end view thereof with certain parts broken away to illustrate the underlying construction.

As in my application afore referred to, the reference numeral 5 indicates the body 45 of a level with which the registering element 6 is associated, it being understood that the level may be of any desirable character, and material, and that these elements may be in the nature of tubes or other 50 elements, as is most desirable.

Referring to the construction of the attachment it will be seen that the same primarily includes a preferably U shaped plate 55 7 formed with a cutout portion 8, this cutout portion, when the plate is in applied position, aligning with a slot 9 in the body 5

of the level for a purpose hereinafter brought out.

Also the body of the level is formed with a transversely extending opening which intersects the cutout portion 9, and mounted within this latter opening is a screw threaded stem 10, a shoe 11 being secured to the lower end of this stem, while a plate 12 is mounted upon the upper end thereof. Also 60 this plate is formed with downwardly extending end portions 13 terminating in pointers 14 which are adapted to register with graduations 15 formed on the exterior face of the plate. 70

Now with a view of moving the stem 10 transversely with respect to the body of the level, it will be seen that the cutout portion 9, and the opening 8 of the plate accommodate the screw threaded washer 16, which 75 latter includes the threads of the stem 10. Thus upon an operator rotating the thumbscrew 16 it will be understood that the stem 10 will be prevented from rotating incident to the flattened shoe 11, but this stem, together with the said shoe will be caused to move transversely of the level body 5. 80 Also incident to the association of the plate 12 with the stem the latter will be prevented from rotating, and the outer portions of 85 the same will slide along the exterior faces of the plate 7 and serve by means of the pointers 14 and graduations 15 to indicate the position of the stem.

Thus an operator is enabled to place the 90 level upon a supporting surface, and to actuate the washer 16 to cause the same to be positively moved in the manner afore-described, and when the shoe 11 elevates one end of the level to a point at which the indicating elements 6 of the same show that the body of the level is in a horizontal plane an operator may accurately determine the distance to be measured by reading the 95 graduations 15 by means of the pointers 14. 100

Obviously numerous modifications of structure might readily be resorted to without in the least departing from the scope of my claims; which are:

1. A level attachment including a plate, a 105 stem, a shoe forming a part of said stem, means for moving said stem with respect to said plate, and a second plate carried by the upper end of said stem and having a portion downbent and terminating in a pointer 110 lying opposite the first-mentioned plate, the latter plate carrying a scale having gradu-

tions with various of which said pointer is adapted to align as said stem is moved.

2. A level attachment including a screw threaded stem, a plate formed with an opening, a thumb-screw engaging the screw threads of said stem and extending within the opening of said plate, a shoe formed at the lower end of said stem, a second plate

carried by the upper end of said stem, said latter plate being formed with downwardly turned end portions terminating in pointers, said pointers being adapted to align with graduations formed in said first named plate.

LEVERETT W. TIFFANY.
